UNITED STATES PATENT OFFICE.

BENJAMIN GARVIN, OF OSHKOSH, ASSIGNOR OF ONE-HALF HIS RIGHT TO
HENRY HULL, OF FOND DU LAC, WISCONSIN.

IMPROVEMENT IN SPARK-ARRESTERS FOR LOCOMOTIVES.

Specification forming part of Letters Patent No. 119,928, dated October 17, 1871.

To all whom it may concern:

Be it known that I, BENJAMIN GARVIN, of Oshkosh, in the county of Winnebago and State of Wisconsin, have invented a new and Improved Spark-Arrester for Locomotives; and I do hereby declare the following to be a full, clear, and exact description of the same, reference being had to the accompanying drawing forming part of this specification, in which—

Figure 1 is a vertical central section of a locomotive smoke-stack, showing the application of my improvements. Fig. 2 is a transverse section of the same taken in the plane of the line $x\ x$, Fig. 1.

Similar letters of reference in the accompanying drawing indicate corresponding parts.

My invention has for its object to provide a spark-arrester for locomotives which shall be more economical in construction and efficient in operation than those now in use; and to this end the invention consists in an improved construction of the same, as hereinafter set forth.

In the accompanying drawing, A is the smoke-stack of a locomotive-engine mounted upon the bridge-plate in the usual manner. B is the smoke-pipe, placed concentrically within the stack, extending upward from the bridge-plate about one-half or two-thirds the length of the stack, and is held in place near its lower end by the band C, which is supported from the stack by short bars or rods D. The lower end of this pipe receives the ends of the exhaust-pipes in the usual manner. E is the truncated conical deflector, supported from the end of the smoke-pipe about on a line with the top of the stack by means of the rods F and nuts G.

The parts thus far described are in common use in nearly all locomotives, and do not, in themselves, constitute my invention, but form the basis of its application, as I will now proceed to describe.

H is a diaphragm placed midway of the stack and provided with a central opening to receive the end of the smoke-pipe B, which fits therein with close contact; or the smoke-pipe may terminate immediately under the plate, if preferred, the diameter of the pipe and of the opening in the plate being equal, or nearly so. From the circular opening the diaphragm is inclined down-

ward to the stack to form a shallow receptacle for the accumulation of sparks. I is an annular plate secured to the outer edge of the conical deflector and extending inward toward the apex of the same to form a chamber, J, as shown in Fig. 1. This chamber communicates with the stack below the diaphragm by means of short tubes or diving-flues K, which are secured to the annular plate around suitable openings formed therein, and extend downward through the diaphragm.

The operation is as follows: When the engine is in motion and exhausting through the pipe B, the sparks from the fire-box are carried upward through said pipe, by the force of the exhaust, until they come in contact with the deflector, by which they are directed into the chamber J. From this chamber they descend, in the form of cinders, through the flues K, into the stack below the diaphragm H and upon the outside of the smoke-pipe, lodging around the base of the latter, from which they may be removed through a door placed at the base of the stack. Those sparks which are still "alive," or containing fire, as they reach the lower end of the smoke-pipe, are drawn up again, by the exhaust, through the openings L at the base of the said pipe and again carried down through the flues below the diaphragm.

Owing to the circuitous course of the sparks, they are thoroughly beaten into fine particles or cinders, a portion of which is expelled with the exhaust through the netting of the smoke-stack, while another portion accumulates upon the top of the diaphragm, from whence it may be removed from time to time. Owing to the arrangement of the diaphragm, the force of the exhaust does not affect the sparks or cinders as they escape from the ends of the diving-flues, so that they readily fall to the base of the smoke-pipe, where they lodge or are again carried up by the exhaust, as above described.

Having thus described my invention, what I claim as new is—

1. The conical deflector E, constructed with an annular plate, I, as described, for the purpose specified.
2. In a locomotive smoke-stack, the combination of two chambers connected by diving-flues,

one chamber, J, formed by the annular plate I and the deflector E, being arranged to receive the live sparks from the exhaust, and the other chamber, formed by the diaphragm H, being arranged to receive the spark-cinders after they have passed through the first chamber, substantially as described, for the purpose specified.

3. The diaphragm H, annular plate I, and flues

K, in combination with the stack A, deflector E, and smoke-pipe B, substantially as described, for the purpose specified.

BENJAMIN GARVIN.
